US00D489053S

(12) **United States Design Patent** (10) Patent No.: **US D489,053 S**
(45) Date of Patent: ** Apr. 27, 2004

(54) **RECORDING MEDIA**

(75) Inventor: **Toshihiro Nakamura**, Tokyo (JP)

(73) Assignee: **Sony Corporation**, Tokyo (JP); .

(**) Term: **14 Years**

(21) Appl. No.: **29/182,935**

(22) Filed: **Jun. 4, 2003**

(51) LOC (7) Cl. **14-01**

(52) U.S. Cl. **D14/167**

(58) Field of Search **D14/156-157, D14/160-165, 167-168, 188-189, 217-218, 299, 496; 312/7.1; 369/75.1, 75.2, 77.1, 77.2; 455/344, 347-351**
